HIS ATTORNEY

UNITED STATES PATENT OFFICE.

HERBERT H. STEELE, OF MARCELLUS, NEW YORK, ASSIGNOR TO THE MONARCH TYPEWRITER COMPANY, OF SYRACUSE, NEW YORK, A CORPORATION OF NEW YORK.

TYPE-WRITING MACHINE.

1,021,953.

Specification of Letters Patent.

Patented Apr. 2, 1912.

Application filed November 28, 1910. Serial No. 594,535.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My present invention relates especially to inking mechanism for typewriting machines and its general object is to provide improved devices of the character specified.

More specifically, one object of my invention is to provide devices which, while they may be employed with the usual ink ribbon, are particularly adapted for use with a ribbon or strip of carbon paper or the like.

One object of my invention is to provide devices of the character last referred to which may be readily and cheaply adapted to existing forms of typewriting machines.

To the above and other ends my invention consists in the features of construction, combinations of devices and arrangements of parts hereinafter described and particularly pointed out in the claims.

In carrying out my invention in the present instance I have shown it applied to a Monarch typewriting machine but the nature of the invention is such that it may be easily applied to other forms of writing machines.

With the usual form of ribbon feed mechanism the ribbon is advanced by the turning of the receiving ribbon spool, which spool is revolved through connections with the carriage power. The result is that the rate at which the ribbon is fed varies for the reason that when the amount of ribbon wound on the receiving spool is small the longitudinal advance of the ribbon is slow and as the amount on the spool, or what may be termed the "core", increases in diameter, the longitudinal advance of the ribbon increases in extent with respect to the advance of the carriage. Consequently, for a unit's distance of travel of the carriage the corresponding travel of the ribbon will continuously increase until the receiving spool is full. Then when the direction of feed of the ribbon is reversed, the same continuous increase of ribbon travel in the opposite direction will occur while the ribbon is winding on the other spool. This mode of feeding, while it has proved satisfactory

with the usual inking fabric, has disadvantages when employed in connection with a paper ribbon where a single impact of the type-face drives practically all the carbon or inking material beneath the type face from the paper ribbon on to the work sheet. It is consequently highly desirable to provide a longitudinal feed which shall be constant or uniform for the carbon paper and also a feed that at each letter space movement shall be of sufficient extent to enable the vertical portions or bars of successive character impressions to clear each other. These desiderata require that the longitudinal travel of the ribbon shall not be less than $1/64''$ for each letter space movement of the carriage and shall not vary. My invention as herein exemplified accomplishes these results. It is further desirable, in order to avoid waste, that the ribbon feed shall be cut out or rendered inoperative whenever the carriage is released for a continuous advance of greater or less extent either by operating the release key or by a tabulator key. To this end connections are made with the usual tabulating key of the machine and also with the release key, so that when either of said keys is actuated, causing the release of the carriage, the ribbon feeding devices are cut out or rendered inoperative and no advance of the ribbon will take place during the continuous advance of the carriage.

Specific features of the present form of my invention will be described in detail in connection with the accompanying drawings, 90 wherein—

Figure 1 is a fragmentary vertical front to rear sectional view of the upper part of a Monarch typewriting machine embodying my invention. Fig. 2 is a fragmentary plan view of the upper part of said machine. Fig. 3 is a fragmentary front elevation partly in section showing details of the carriage releasing mechanism and ribbon cut-out devices. Fig. 4 is a vertical sectional view of the delivery spool or carrier and the mounting of the same. Fig. 5 is a horizontal sectional view of the devices which directly engage with the ribbon and feed the same lengthwise.

In the various views parts are omitted and broken away and only so much of the machine is shown as is necessary to a clear understanding of the invention.

Referring especially to Fig. 1, the main

frame of the machine comprises posts 1 supporting a top plate 2 from which rise standards 3 to which are secured longitudinally grooved track rails 4. Said track rails 5 operate with anti-friction balls 5, which balls also engage top and bottom grooves in a slide bar 6, said slide bar being comprised in a platen frame or carrier which further includes end bars 7 extending forward from the ends of the slide bar and supporting an axle 8 of a rotary platen 9. Key controlled printing instrumentalities (not shown) coöperate with the front face of said platen which is provided with the usual or suitable line-spacing devices. The platen and platen carrier or carriage are power driven, being constantly urged leftward by a carriage power or spring drum 10 which is connected with the carriage by a band or strap 11. Arms 12, pivoted each at 12^a on the end bars 7 support a feed rack 13 which is normally maintained by spring means 14 in mesh with a feed pinion 15 which is operatively connected with a toothed escapement wheel 16. Coöperating with the escapement wheel are other escapement devices or dogs (not shown) which are controlled by the printing keys, so that at each actuation of a printing key the escapement devices co-act to permit a letter space advance movement of the carriage under the pull of the spring drum 10. The carriage may be released from the escapement devices by a depression of one or another of the release keys 17, one of which is arranged at each end of the carriage and is rigidly connected to the contiguous pivot portion 12^a of the associate arm 12, the construction being such that the depression 30 of either release key operates to lift the feed rack 13 from the pinion 15. The carriage is also adapted to be released by the operation of a tabulator key 18. Said key, as heretofore, is secured at the front end of a push rod 19 which bears in the right-hand front corner post and is pivotally connected at its rear end with the upright arm of a bell crank 20, the other arm of said bell 40 crank being connected by a link 21 with the right-hand arm of a lever 22 fulcrumed at 23 in a bracket 24. Said lever 22 is pivotally connected at 25 with a lifter 26 having shoes 27 underlying the feed rack 13 and adapted to lift the same from engagement 50 with the pinion 15 when the tabulator key 18 is pushed in. Secured as by rivets 28 to the lifter 26 and extending upward behind the feed rack is an extension 29 which is adapted to engage with a tabulator stop 30 pivoted at 31 to a fixed bracket 32 and provided with a spring 33 which normally maintains said stop in the position shown in Fig. 1. The operation of the tabulator key 18 lifts the extension 29 and causes it to swing the frame stop 30 down

into the path of column stops 34 mounted on a stop bar 35 carried by the carriage. As the operation of the tabulator key 18 also releases the carriage as heretofore explained, said carriage will move continuously leftward until arrested by the engagement of one of the column stops 34 with the frame stop 30. The operation of the tabulator mechanism need not be further explained herein. 75

Referring now to the novel parts of my present invention, I preferably employ for printing purposes a narrow paper strip or ribbon 36 which replaces the usual inked fabric or ribbon. The strip or ribbon 36 is of thin material and preferably is covered with carbon or other inking material on one surface only, namely, the inner surface or that one which faces the printing face of the platen. The inking strip or carboned-paper strip or ribbon is preferably narrower than the ordinary ribbon which it replaces, the strip 36 shown in the present case being 5/16" in width. The inking strip 36 is wound on a core piece or annulus 37 of pasteboard or the like and forms a supply roll which is adapted to fit into the left-hand spool cup or container 38, heretofore provided on the top plate of the machine (Fig. 4). To support the supply roll I provide a holder comprising a disk 39 which fits within the spool cup and is supported in turn on the hub portion 40 of a shaft 41 which turns in a fixed bearing 42 integral with the top plate. A collar 43 pinned at 44 to the lower end of the shaft 41 below the bearing 42 prevents accidental displacement of the shaft 41. The upper portion 41^a of the shaft 41 is enlarged and projects above the hub portion 40. The disk 39 is forced down over the shaft portion 41^a into contact with the top of the collar 40 and is suitably secured in place. Projecting upward from the disk 39 are a plurality of pointed pins 45, four in the present instance, arranged so that the core 37 will fit loosely over them. The pins 45 thus provide a four-point bearing for the supply roll of carbon paper and enable it to turn freely thereon and independently of the disk 39. The supply roll holder also comprises a companion disk or flange 46, which fits down over the shaft portion 41^a and provides a cover for the supply roll. Said disk 46 is provided with a sleeve or hub portion 47 which fits over the shaft and contacts at its bottom with the disk 39 and is of such length as to hold the disk 46 out of contact with the supply roll 36. 110

The loose or free end of the carbon strip 120 is let off from the supply roll passing through a cutaway or slot 48 formed in the left-hand spool cup at the inner side thereof. Centrally of the machine the paper strip is threaded through a vibratory ribbon 130

carrier or vibrator 49 which is of the usual or suitable construction. The vibrator shown in the present instance is of the ordinary style, the only difference being that the guide slots through which the paper strip is threaded have their bottom portions somewhat higher than is usual, in order to compensate for the narrowness of the paper strip. The vibrator is or may be connected with the usual operating devices of the Monarch machine including an operating lever 50, said devices being actuated from the printing keys so that at printing operation the operating lever 50 is turned on its fulcrum and lifts the vibrator 49 from normal position below the printing point as shown in Fig. 1 until the paper strip 36 is presented opposite the printing point. In its vibratory movements the ribbon carrier or vibrator is guided by an upright guide 51 secured to the top plate.

The paper ribbon 36 is drawn off the supply roll at the left-hand side and fed step-by-step through the vibrator by devices at the right-hand side of the machine and some of which are within the right-hand spool cup 38, said spool cup being cut away at its rear side as indicated at 52 to permit the strip feeding devices to coöperate properly. Said strip feeding devices comprise a rotary driving member or wheel 53 of large diameter which is arranged in the right-hand spool cup 38, as appears from Figs. 1 and 2. The wheel 53 comprises a core 54 of wood or the like which is covered by a sheath 55 preferably of rubber. The wheel 53 is provided with a bottom flange 56 and a top flange 57 and is driven on or otherwise secured to the upper end portion 58 of a vertically arranged shaft 59 which turns in a bearing 60 fixed to the top plate and depending therefrom. The driving wheel as a whole is seated on an enlargement or hub 61 on the shaft 59, said hub engaging a boss 2^a on the top plate.

The driving member or wheel 53 is connected with the spring drum 10 so as to receive motion therefrom by connections which comprise a bevel gear wheel 62 secured to the lower end of the shaft 59 and engaging at its upper face with a small beveled pinion 63 fixed to the forward end of a horizontal shaft 64, said shaft turning in lugs 65 depending from the top plate. Fixed to the rear end of the shaft 64 is a beveled gear wheel 66 which is constantly in mesh with a beveled pinion 67 (Figs. 1 and 2) secured to the right-hand end of a power or driving shaft 68, said shaft extending horizontally beneath the top plate and turning in bearings 69 depending therefrom. Fixed to the left-hand end of the driving shaft 68 is a small beveled gear 70 which constantly meshes with a corresponding gear 71, said gear being connectible by a pawl 72 and

ratchet wheel 73 with the spring drum 10 so as to receive motion from said spring drum when it is turning to advance the carriage in printing direction. It will be observed that the connections between the spring drum and the wheel or driving member 53 correspond substantially with the connections heretofore employed between the spring drum and the ribbon spools. However, in the present instance the driving shaft 68 is not movable endwise but is maintained so that the pinion 67 and the gear wheel 66 are always in mesh.

Co-acting with the sheath or periphery 55 of the driving wheel is a small wheel or roller 74 having an outer surface of rubber or the like, said roller being arranged midway in the opening or slot 52 and being pivoted on an upright stud or screw pin 75 secured to the rearwardly extending arm 76 of a hand lever 77 which is fulcrumed at 78 to a stud rising from the top plate, the hand lever extending forward below the driving wheel and having an arm 79 which extends through a slot 38^a in the right-hand spool cup, said arm 79 terminating in an upright key or finger piece 80 in front of said spool cup. Said hand lever 77 further comprises an arm 81 extending rightward from the arm 76 and bent downward at right angles providing a vertical arm or extension 82 which extends through a slot 83 in the top plate 2. A coiled spring 84 connects the arm 81 of the lever 77 with an arm or anchor 85 secured by a screw 86 to the top plate, said spring, as will be apparent from Fig. 2, tending constantly to maintain the roller 74 in frictional engagement with the periphery of the driving wheel 53. On loosening the screw 86 the arm 85 may be adjusted to vary the tension of the spring 84. By pressing the special key or finger piece 80 toward the right the spring 84 may be overcome and the roller 74 moved rearward out of engagement with the wheel 53, thus enabling the paper strip 36 to be arranged between said roller and said wheel so that said strip will be frictionally engaged by these co-acting rotary devices when the finger piece 80 is released, permitting the spring 84 to restore the roller 74.

As appears from Fig. 1 the height of the roller 74 is less than the distance between the flanges 56 and 57 of the driving wheel so that said roller may pass freely between said flanges into engagement with the surface of the driving wheel or with the paper strip. The height of the guiding wheel or its width between the flanges 56 and 57 is such that the narrow carbon strip 36 may readily be accommodated and the diameter of the driving wheel is such that the turning of the spring drum step-by-step to advance the carriage letter space distances will cause the driving wheel to turn step-by-step to

such an extent that the carbon strip 36 will be advanced at a uniform rate by reason of the frictional feed between the driving wheel 53 and the roller 74, which rate is 5 of sufficient extent to cause the upright portions of successive type impressions to clear each other. The result is that the carbon strip will be used uniformly throughout its entire length. Since one set of type impressions 10 practically exhausts the carbon carried by the rear or inner surface of the printing portion of the strip, the used portion of the carbon strip may be torn off and thrown away after it passes to the right and 15 from between the feed devices 74 and 53.

Guiding devices are provided to insure that the paper strip 36 shall always operate properly with the feed rollers 53 and 74. Said devices comprise a hook-like 20 guide 87 (Figs. 1 and 2) secured to the rim of the right-hand spool cup 38 at the left of the opening 52. The closed end of the hook or guide 87 is uppermost so that the paper strip or ribbon will be prevented from rising 25 even if it should escape from under the flange 57. A similar hook-like guide 88 may be arranged at the right of the opening 52 and mounted on the rim at the right-hand spool cup 38. The closed portion of the 30 hook or guide 88 is at the bottom instead of at the top so that the paper tape or ribbon will be prevented from dropping down out of the control of its feeding devices.

In order to insure that the feeding devices 35 shall be rendered inoperative when the tabulating mechanism is actuated to cause a continuous run of the carriage, connections are provided between the tabulating mechanism and the roller 74, such that when the tabulating key 18 is pressed in, the roller 40 74 will be moved out of operative engagement with the wheel or roller 53. Said connections comprise a swinging arm 90 which is pivoted at 91 to a bracket 92 fixed to and depending from the top plate 2, the arm 90 being so mounted that it will swing freely 45 fore and aft of the machine. A finger or lug 93 is secured to the push rod 19 by a set screw 94, said finger projecting horizontally 50 leftward from the push rod 19 in front of the swinging arm 90 and in position to contact with the lower portion of said arm when the tabulator key 18 is pushed in, the construction being such that the finger 93 then acts to swing the arm 90 rearward on its pivot 91. The arm 90 is provided with a lateral extension 90^a and this rearward movement of said arm causes the extension 90^a to act against the lower end of the downward extension 82. The result is that as the 55 arm 90 swings rearward it acts through the extension or offset 90^a to turn the lever 77 on its pivot 78 and move the roller 74 out of co-operative engagement with the paper strip or ribbon. In other words, the actua-

tion of the tabulating mechanism operates automatically to separate the feeding devices for the paper strip or ribbon 36 and renders said feeding devices inoperative.

Means are also provided for separating 70 or rendering inoperative the paper strip feeding devices when one of the release keys 17 is actuated, said means comprising connections between the feed rack 13 and the extension 82 of the lever 77. Said connections include a lip 95 suitably secured to the feed rack 13 and projecting horizontally rearward therefrom, said lip extending longitudinally of said feed rack and under the horizontally bent upper portion 96 of a 80 vertical extension 97 formed at the end of the left-hand arm of a lever 98 having a fixed fulcrum 99. The means as thus far described and comprising the lip 95 and lever 98 are included in the rack lock mechanism of the Monarch machine and need not be further set forth herein. It will be understood that during the to and fro movements of the carriage the lip 95 runs along beneath the horizontal portion 96 of the lever 98 so that if at any time the carriage is released by depressing one of the keys 17 and raising the feed rack 13, the lip 95 will act on the part 96 to turn the lever 98, lifting that portion of the lever to the left 90 of the fulcrum 99 and lowering the portion or arm at the right of said fulcrum.

In carrying out my invention I provide an extension from the right-hand arm of the lever 98, said extension being formed 100 preferably integral with said lever arm although it need not be. Said extension comprises a downwardly bent portion 98^a and an angular horizontal portion composed of a forward extension or offset 98^b and a 105 rightward extension 98^c from the forward end of said offset. The end or portion 98^c is seated in a notch 100 in the forward end of the horizontal arm 101 of a bell crank 102. Said bell crank is fulcrumed at 103 110 to a bracket or lug 104 fixed to and depending from the top plate 2. The bell crank 102 further comprises a depending arm 105 which is pivotally connected at 106 with a 115 forwardly extending horizontal link 107, the forward end of said link being connected at 108 with the extension 82. It will be understood that when one of the keys 17 is actuated to release the carriage by lifting the feed rack 13 the right-hand arm of the lever 98 will be depressed and the extension 98^c will act on the lever arm 101 to swing it downward about the pivot 103, the other arm 105 of the bell crank 102 being 120 swung rearward a corresponding extent. This rearward movement of the arm 105 pulls the link 107 rearward, said link acting through the arm 82 to swing the lever 77 on its pivot and throw the feed roller 74 out of action. In other words, the release of 130

the carriage by one of the keys 17 operates automatically to disconnect the feeding devices for the paper strip so as to render them inoperative.

5. Various changes may be made without departing from my invention, and parts may be used without other parts.

What I claim as new and desire to secure by Letters Patent, is:—

10. 1. The combination of a carriage that is fed step-by-step for letter spacing, carriage driving mechanism, a paper ribbon supply device, means for constantly drawing the paper ribbon uniform extents from said supply device during the step-by-step movements of the carriage, and connections between said means and the carriage driving mechanism, said means feeding the paper ribbon out of the machine, the arrangement 20 permitting the paper ribbon readily to be torn away after passing said means.

25. 2. In a typewriting machine, the combination of a carriage, carriage driving mechanism, carriage releasing means, ribbon feeding mechanism comprising devices co-acting with each other through the ribbon, constantly operative connections between said carriage driving mechanism and certain of said devices, and means operative 30 by said carriage releasing means for rendering said devices inoperative to feed the ribbon.

35. 3. In a typewriting machine, the combination of a carriage, carriage driving means, carriage releasing means, ribbon feeding mechanism comprising devices for frictionally feeding the ribbon, constantly operative connections between certain of said devices and said carriage driving means, and means 40 operative by said carriage releasing means for rendering said frictional feeding devices inoperative.

45. 4. In a typewriting machine, the combination of a carriage, carriage driving mechanism, carriage releasing means, ribbon feeding mechanism comprising devices co-acting with each other through the ribbon, constantly operative connections between said carriage driving mechanism and certain of said devices, and means operating 50 automatically to render said devices inoperative to feed the ribbon.

55. 5. In a typewriting machine, the combination of a carriage, carriage driving mechanism, carriage releasing means, feed rollers for frictionally feeding the ribbon, and means operative by said carriage releasing means for separating said feed rollers and thereby rendering said feed rollers inoperative.

60. 6. In a typewriting machine, the combination of a carriage, carriage driving mechanism, carriage releasing means, means for constantly feeding an inking ribbon a uniform extent with relation to the carriage

travel, constantly operative connections between said feeding means and the carriage driving mechanism, and means connected with said releasing means operative on the ribbon feeding means for rendering the ribbon feeding means inoperative.

7. In a typewriting machine, the combination of a carriage, carriage driving mechanism, carriage releasing means, means for constantly feeding an inking ribbon a uniform extent with relation to the carriage travel, constantly operative connections between said feeding means and the carriage driving mechanism, and means operative on the ribbon feeding means for automatically rendering the ribbon feeding means inoperative during the carriage travel.

8. In a typewriting machine, the combination of a carriage, carriage driving mechanism, carriage releasing means, means for constantly feeding an inking ribbon a uniform extent with relation to the carriage travel, constantly operative connections between said feeding means and the carriage driving mechanism, and means controllable 90 by a key and operative on the ribbon feeding means for rendering the ribbon feeding means inoperative during the carriage travel.

9. In a typewriting machine, the combination of a carriage, carriage driving mechanism, carriage releasing means, means for constantly feeding an inking ribbon a uniform extent with relation to the carriage travel, constantly operative connections between said feeding means and the carriage driving mechanism, and means controllable 100 both automatically and also by a special key and operative on the ribbon feeding mechanism independently of said connections for rendering said ribbon feeding mechanism inoperative.

10. In a typewriting machine, the combination of a carriage, carriage driving mechanism, a carriage release, key controlled tabulating mechanism, means for constantly feeding an inking ribbon a uniform extent with relation to the carriage travel, constant connections between said feeding means and the carriage driving mechanism, and devices 115 under the control of said tabulating mechanism for rendering said feeding mechanism inoperative.

11. In a typewriting machine, the combination of a carriage, carriage driving mechanism, a carriage release, key controlled tabulating mechanism, means for constantly feeding an inking ribbon a uniform extent with relation to the carriage travel, constant connections between said feeding means and the carriage driving mechanism, and devices 120 operative by a special key and by said carriage release and also by said tabulating mechanism for rendering said feeding mechanism inoperative.

12. In a typewriting machine, the combination of a carriage, carriage driving mechanism, key controlled tabulating mechanism, ribbon mechanism comprising co-acting feed rollers for frictionally feeding the ribbon, and devices for separating said feed rollers, said devices being operative by a special key and also by said tabulating mechanism. 5
13. In a typewriting machine, the combination of a carriage, carriage driving mechanism, a carriage release, key controlled tabulating mechanism, ribbon mechanism comprising co-acting feed rollers for frictionally feeding the ribbon, and devices for separating said feed rollers, said devices being operative by a special key and automatically when said tabulating mechanism is operated and also when said carriage release is operated. 10
14. In a typewriting machine, ribbon mechanism comprising co-acting feed rollers between which the ribbon runs, a spring adapted to maintain said feed rollers in co-action, and means for adjusting the tension of said spring, said means comprising an adjustable arm to which one end of said spring is secured. 20
15. In a typewriting machine, ribbon mechanism comprising co-acting feed rollers between which the ribbon runs, a lever supporting one of said feed rollers, and means tending constantly to turn said lever on its fulcrum, said means comprising a spring, one end of which is secured to an adjustable arm. 30
16. In a typewriting machine, ribbon mechanism comprising co-acting feed rollers between which the ribbon runs, a lever supporting one of said feed rollers, and a finger piece on said lever for controlling the last named feed roller, said lever being housed beneath the other feed roller so that substantially the finger piece only is exposed. 40
17. In a typewriting machine, ribbon mechanism comprising co-acting feed rollers between which the ribbon runs, a lever supporting one of said feed rollers, a spring operative on said lever to maintain the feed rollers in co-action, and a finger piece on said lever operative to overcome said spring, said lever and said spring being substantially housed beneath one of said feed rollers. 50
18. In a typewriting machine, ribbon mechanism comprising co-acting feed rollers between which the ribbon runs, a lever supporting one of said feed rollers, a spring operative on said lever to maintain the feed rollers in co-action, and an adjustable anchor for said spring, said lever, said spring and said anchor being housed substantially by one of said feed rollers. 60
19. In a typewriting machine, ribbon mechanism comprising in combination a supply roll at one side of the machine, a central vibrator through which the ribbon passes from the supply roll, co-acting friction feed rollers at the opposite side of the machine between which rollers the ribbon runs, devices for varying the amount of friction between said feed rollers, and means for housing said supply roll, said devices and one of said feed rollers. 70
20. In a typewriting machine, the combination of a vibratory ribbon carrier centrally arranged, a ribbon supply roll at one side of said carrier, friction feed rollers for the ribbon at the opposite side of said carrier, a traveling carriage, a carriage release, and means connected to said carriage release for separating said feed rollers. 75
21. In a typewriting machine, the combination of a vibratory ribbon carrier centrally arranged, a ribbon supply roll at one side of said carrier, friction feed rollers for the ribbon at the opposite side of said carrier, a traveling carriage, and means operative automatically when the carriage is released for separating said feed rollers. 80
22. In a typewriting machine, the combination of a carriage, carriage driving mechanism, a centrally arranged vibratory ribbon carrier, spool cups on the frame of the machine at opposite sides of said carrier, a ribbon supply roll on one of said cups, a friction feed roller in the other cup, connections between said feed roller and the carriage driving mechanism, and a second feed roller co-acting with the first-named feed roller. 90
23. In a typewriting machine, ribbon mechanism comprising co-acting feed rollers, and stationary guides for preventing the ribbon from either dropping or rising from between said feed rollers, said guides being at opposite sides of said feed rollers. 95
24. In a typewriting machine, the combination of a carriage, carriage driving mechanism, a carriage release, ribbon feed rollers between which the ribbon runs, a lever supporting one of said feed rollers and provided with a finger piece, and connections between said lever and said carriage release. 100
25. In a typewriting machine, the combination of a carriage, carriage driving mechanism, a carriage release, ribbon feed rollers between which the ribbon runs, a lever supporting one of said feed rollers and provided with a finger piece, key controlled tabulating mechanism including a push rod, and connections between said push rod and said lever. 110
26. In a typewriting machine, ribbon mechanism comprising a holder for a ribbon supply roll, said holder comprising a disk carrying a plurality of pins on which the core of the supply roll is adapted to turn, and also a second disk at the opposite 125
- 65 130

side of the supply roll from the first named disk.

27. In a typewriting machine, ribbon mechanism comprising a holder for a ribbon supply roll, said holder comprising a disk carrying a plurality of pins on which the core of the supply roll is adapted to turn, and also a second disk at the opposite side of the supply roll from the first named disk, said second disk being separable from

the first disk and being provided with a sleeve which passes between said pins and co-acts at its end with the first disk.

Signed at Syracuse, in the county of Onondaga, and State of New York, this 25th day of November A. D. 1910.

HERBERT H. STEELE.
